PROTECTION OF METALLIC FILMS FROM GALVANIC REACTIONS ON PHOTOGRAPHIC
LAYERS OR THE LIKE BEING APPLIED TO THEM

No Drawing. Application filed August 9, 1930, Serial No. 474,220, and in Germany May 10, 1929.

When photographic or similar layers are applied to metallic films, for example to thin aluminum foils or films, it is found that when the so-coated films are introduced into photographic baths, that is, the baths for treating the photographic layers, the metal salts dissolved in the bath and deposited on the layers bring about galvanic reactions between such salts and the carrier metal which leads to the deterioration of the photographic layer and to corrosion of the carrier metal.

Similar deleterious galvanic reaction may take place not only in the photographic bath; but also in applying or drying the photographic layer.

The present invention relates to means to prevent or greatly reduce such galvanic action. As the salts, above referred to, are either more negative or more positive than the carrier metal, the salt and the metal form a galvanic couple with a resultant electromotive force. By applying during the process of bathing, drying or applying of the sensitive layer on the film, a weak unidirectional current, the deleterious influence of the above galvanic action can be prevented.

Instead of applying a weak continuous current, a pulsating current may be applied either by repeatedly opening or closing the circuit, or by increasing or decreasing the amplitude of the current.

What we claim is:—

1. A step in the process for treating metallic photographic films in liquid baths containing solutions of metallic salts, comprising passing an electric current through the carrier metal in such bath in such direction as to "buck" and nullify the effect of the galvanic current due to the difference of potential set up between the metallic film and the metal in the salt bath.

2. A step in the process for treating metallic photographic films in liquid baths containing solutions of metallic salts, comprising passing a weak direct current through the carrier metal in such bath in such direction as to "buck" and nullify the effect of the galvanic current due to the difference of potential set up between the metallic film and the metal in the salt bath.

3. A step in the process for treating metallic photographic films in liquid baths containing solutions of metallic salts, comprising passing a pulsating electric current through the carrier metal in such bath in such direction as to "buck" and nullify the effect of the galvanic current due to the difference of potential set up between the metallic film and the metal in the salt bath.

In testimony whereof we have signed our names to this specification.

CHRISTIAN SEMENITZ.
SIEGFRIED LOEWENTHAL.
